DESIGN FOR A LACE COLLAR OR SIMILAR ARTICLE

Elsa Schiaparelli, New York, N. Y.

Application November 14, 1940, Serial No. 96,586

Term of patent 3½ years

To all whom it may concern:

Be it known that I, Elsa Schiaparelli, a citizen of France, residing in the city, county, and State of New York, have invented a new, original, and ornamental Design for a Lace Collar or Similar Article, of which the following is a specification, reference being had to the accompanying drawing, forming a part thereof.

The figure is a plan view of a lace collar or similar article showing my new design, it being understood that the part shown in full lines is repeated on the part shown in broken lines as indicated.

I claim:

The ornamental design for a lace collar or similar article, as shown and described.

ELSA SCHIAPARELLI.
